T. G. MARTIN

AUTOMATIC TELEPHONE SYSTEM

Original Filed March 3, 1922

Inventor:
Talbot G. Martin
Att: Walter Davis, Atty.

Patented Apr. 13, 1926.

UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed March 3, 1922, Serial No. 540,890. Renewed July 25, 1925.

To all whom it may concern:

Be it known that I, TALBOT G. MARTIN, a citizen of the United States of America, and a resident of Chicago, Cook County, and 5 State of Illinois, have invented certain new and useful Improvements in Automatic Telephone Systems, of which the following is a specification.

The present invention relates in general to 10 automatic telephone systems, and more especially to large automatic systems which employ both primary and secondary line switches for the purpose of connecting calling lines with idle first selector switches; 15 and the object of the invention is the provision of certain improvements in a system of this kind which tend to increase its commercial utility. In particular the invention contemplates the use of secondary line 20 switches of the rotary type, and improved arrangements are shown whereby such switches may be used to advantage in conjunction with primary line switches of the well known Keith or plunger type.

25 In systems of this general character, it has been customary to provide an arrangement of chain relays for a group of secondary line switches which will operate to make all the secondary line switches busy to the primary line switches whenever all of the trunk lines accessible to the group of secondary line switches become busy. This busying means, however, does not become effective until the last trunk line has actually been taken for 30 use by a secondary line switch, and it may happen therefore that two or more secondary line switches are seized and started hunting for trunk lines at a time when there is only one trunk line available. In such a case the first line switch to reach the idle trunk line 35 will take it for use, while the other switch or switches will continue to hunt for trunks. Unless another trunk line becomes idle almost at once, the delay introduced is almost 40 certain to spoil the calls, and the prolonged trunk hunting is consequently of no utility.

In order to suitably care for the above described situation, means is provided for rendering all the secondary line switches of a group inoperative whenever all of the trunks accessible to such group become busy. In addition, since it is desirable to know how often calls are lost because they are not diverted to other groups in time, a meter is pro-

vided which is operated to register the number of times the condition occurs.

The foregoing features will be described hereinafter with reference to the accompanying drawings, which show sufficient of the apparatus in an automatic telephone system 60 to enable the invention to be explained and understood.

Referring to the drawing, the reference character A indicates an automatic telephone substation of the ordinary type having the 65 usual talking instrumentalities and a calling device S for controlling the automatic switches at the exchange.

The line conductors 11 and 12 terminate at the exchange in the individual line switch C, which is a switch of the well known Keith or plunger type, and therefore will not need to be described in detail. Briefly stated, the function of the line switch C is to 70 extend the associated line when calling to an 75 idle trunk line.

In accordance with the usual practice, the lines entering the exchange are divided into groups, and all of the line switches associated with the lines in each group may be 80 controlled in their trunk selecting operations by a common master switch. The master switch which is associated with the group which includes the line switch C is shown in the lower left hand corner of the drawing 85 and is indicated by the reference character MS. The function of the master switch MS, as is well known, is to maintain the plungers of all idle line switches opposite an idle 90 trunk line.

Secondary line switches are employed in the present system and accordingly the trunk lines from the primary line switchboards will extend to secondary line switches rather than to first selector switches. The arrangement 95 of the trunking between the primary and secondary line switchboards is well understood. There may be a plurality of groups of secondary line switches and each group of primary line switches will have outgoing 100 trunks extending to the secondary line switches in each secondary group, so that any subscriber calling will be given access to the trunk lines outgoing from all the secondary groups. In this manner a large number 105 of first selectors, say one hundred or more, may be combined in one large group to secure an increased trunking efficiency.

The advantages gained by the use of secondary line switches, however, are well known and need not be discussed in detail.

One of the trunk lines outgoing from the 5 primary group which includes the line switch C is shown in the drawing and extends to the secondary line switch D. The line switch D is of the well known rotary type in which the wipers have no normal 10 positions and move in a forward direction only.

The reference character E indicates a 15 selector switch of the well known Strowger vertical and rotary type of which only a portion of the circuits are shown.

To the right of the master switch MS is shown a relay group which has certain 20 functions to perform when all of the trunk lines outgoing from the secondary line switch group which includes the line switch D become busy. It will be more convenient, however, to describe their functions and operation later on during the explanation of the operation of the system.

Having briefly described the apparatus involved, its operation will now be described 25 more in detail with a view to pointing out the particular features of novelty disclosed herein. For this purpose it will be assumed 30 that the subscriber at substation A desires to call some other subscriber in the system, and the operation of the primary and secondary line switches C and D in connecting the line of substation A to a trunk line extending to a first selector switch will be 35 described. When the receiver at substation A is removed a circuit is completed over the line conductors 11 and 12 for the line relay 14 of the line switch C. Upon energizing, the line relay 14 closes a circuit for 40 the pull in winding 15 of the line switch C at armature 23. Upon energizing, the pull in winding operates both the cut-off armature 21 and the plunger arm 22, the former being effective to disconnect the line conductors 12 and 11 from the winding of the 45 line relay and from ground, respectively; while the latter forces the bank springs 30, 31, 32, and 33 into engagement with contacts 34, 35, 36, and 37, respectively. By 50 the engagement of bank springs 30 and 33 with contacts 34 and 37, the line conductors 11 12 are extended into connection with the trunk line conductors 40 and 42, and a circuit 55 is accordingly completed for the line relay 50 of the secondary line switch D. The line relay 50 is energized and at its armature 53 a holding circuit for line switch C is completed, which may be traced from 60 ground by the way of the working contact of armature 53 and said armature, normally closed contact springs controlled by armature 58, release trunk conductor 41, contact 35, bank spring 31, and the holding winding 16 of the line switch C to battery. This

holding circuit is established before the slow acting line relay 14 of the line switch C has had time to deenergize and is effective to retain the plunger arm 22 and the cut-off armature 21 in an operated position. A 70 ground potential is also placed on the private normal conductor 13 which is connected with the multiple test contacts in the banks of the connectors which have access to the line of substation A, whereby the line is guarded 75 against intrusion in the customary manner.

A circuit for the master switch MS is closed by the engagement of bank spring 32 with contact 36. The master switch is thus operated in the usual manner to advance 80 the plungers of all the idle line switches in the group into position in front of the next idle trunk.

When the line relay 50 of the secondary line switch D is energized, as explained 85 before, a circuit is closed at its armature 54 including the winding of the switching relay 51 and the winding of the stepping magnet 52 in series, while at the same time by means of armature 55 the test wiper 66 is 90 connected to this circuit at a point midway between the said relay and said magnet. The operation now depends upon whether the trunk line with which the wipers are in engagement is busy or idle. If the trunk 95 line is busy there will be a ground potential on the test contact engaged by the test wiper 66, the switching relay will be short circuited, and the stepping magnet, which interrupts its own circuit, will operate in the 100 same manner as a buzzer to advance the switch wipers step by step until an idle trunk line is found. When the wipers arrive at an idle trunk line, which we may assume is the trunk line comprising conductors 71, 72, and 73, the test wiper 66 will 105 find no ground potential on the test contact 69, the rotation of the switch will cease, and the switching relay 51, being no longer short circuited, will energize in series with 110 the stepping magnet 52, the latter magnet remaining inoperative on account of the high resistance of the switching relay. Upon energizing, relay 51 connects the incoming release trunk conductor 41 to the 115 test wiper 66 by means of armature 58, and at armature 57 and its working contact locks itself to the grounded release conductor. Ground at the working contact of armature 53 is maintained on the test wiper 66 until a holding circuit from the idle selector E has been established, this ground also rendering the selected trunk line busy. In addition to the foregoing, at armatures 56 and 59 relay 51 disconnects the incoming 120 trunk conductors 40 and 42 from the windings of the relay 50 and from ground, respectively, and extends them by the way of wipers 65 and 67, bank contacts 68 and 70, conductors 71 and 73, and armatures 74 and 125 75. This completes the description of the 130

76 and their resting contacts to the line relay 80 of the first selector switch E.

As selector switches of the type of selector E are well known its operation is well understood and it will be sufficient to state that the line relay 80 is energized over the circuit of the calling line and a circuit is closed for the associated slow acting release relay 81. The latter relay, upon energizing, 10 places a ground potential upon the release conductor 72 at armature 84 and its working contact, thereby establishing a holding circuit for the switching relay 51 of the line switch D, and the holding winding 16 15 of the primary line switch C. This holding circuit, it will be understood, is established before the slow acting line relay 50 has had time to deenergize.

The act of grounding release conductor 20 72, in addition to establishing the above mentioned holding circuit, completes an energizing circuit for the chain relay 87, and said relay maintains its armature in an operated position as long as the trunk line is 25 busy. The chain relays, of which only a portion are shown, are energized in this manner when the trunk lines with which they are associated become busy. Each chain relay upon energizing closes its portion 30 of a chain of contacts through which the circuit for relay 88 is finally completed when all the chain relays are energized.

The remainder of the operations in which the calling subscriber controls the first 35 selector taken for use, and a plurality of other automatic switches through the medium of his calling device S to complete the connection to the desired called line, are well understood and as they have nothing 40 special to do with the present invention, these operations will not be further considered, except to say that when the calling subscriber has finished talking, the restoration 45 of his receiver to the switch-hook causes the automatic switches to restore to normal with the result that ground is disconnected from the release trunk conductor 72. This operation breaks the holding circuit for primary and secondary line 50 switches C and D and said switches are restored to normal position.

Having described the system in a general way, it will be convenient now to explain 55 the novel features which have been incorporated therein.

In order to explain these features we will assume that two subscribers have seized secondary line switches, one of which is the line switch D and the other of which is a line switch in the same secondary group, at a time when the trunk line shown is the only remaining idle selector trunk. Both secondary line switches start hunting for the idle trunk line and it will be assumed that 60 the other line switch, which for convenience

we will call D', seizes the last remaining idle trunk line before the line switch D has time to seize it. When the other line switch, or line switch D' seizes the trunk line its chain relay 87 is energized in the same 70 manner as previously described and completes the energizing circuit for relay 88. The relay 88 removes at its armature 92 and its resting contact the short circuit around the lost call relay 90, and at this 75 time an energizing circuit may be traced for relay 90 as follows: From ground by the way of relay 90, conductor 97, resting contact of armature 59 and said armature, conductor 42, over the subscriber's loop as previously traced to conductor 40, armature 56 and its resting contact, and winding of relay 50 to battery. The line relay 50 is adapted to deenergize in series with relay 80 on account of the high resistance of the winding of relay 90. The relay 90, however, is energized and at its armature 93 a circuit is closed for the lost call meter M. The lost call meter is therefore operated to 90 register the call.

When the line relay 50 of line switch D is deenergized, the circuit for the stepping magnet 52 is opened at armature 55. A busy tone is also transmitted to the calling subscriber at armature 92 and its working contact in the usual manner, by which the subscriber is informed that the desired connection cannot be completed.

The relay 88 at its armature 91 and its working contact completes an energizing circuit for the group busy relay 89. Relay 89, upon energizing, connects ground to the conductor 98 which is normally connected with the release trunk conductor 41. The ground thus placed on the release trunk conductor 41 busys the trunk line in the usual manner. The group busy relay 89 has a conductor, such as conductor 98, for each secondary line-switch in the group and busys all these trunk lines at the same time and in the same manner that the trunk line leading to line switch D is busied, providing of course that the trunk lines in question are not already busy. If the plunger shaft at any primary line switch-board is standing opposite any one of the busied trunk lines leading to this group of secondaries, the master switch MS moves said shaft to bring the plungers into alignment with a trunk line leading to a different secondary group.

It will be noted that the same ground from armature 94 that busys the trunk line extending to line switch D also maintains the plunger of the calling primary line switch C in an operated position so as to prevent the plunging in and out, or fluttering of the said primary line switch, when the relay 50 upon deenergizing removes the 120 original holding ground.

After receiving the busy tone the subscriber hangs up and calls again later on. Upon the restoration of the receiver to the switchhook the automatic switches are released in the same manner as previously explained.

As soon as one of the outgoing trunk lines from this secondary group become idle the chain relay individual thereto deenergizes and opens the circuit of relay 88, which relay upon deenergizing restores the relays 89 and 90 to their normal positions. By the deenergization of relay 90 the circuit for the lost call meter is opened, allowing said meter to restore to normal, while the deenergization of relay 89 removes the busy condition from the secondary line switch.

Having described the invention, what I consider to be new and desire to have protected by Letters Patent will be pointed out in the appended claims.

What I claim is:

1. In a telephone system, subscribers' lines, a group of trunk lines, a group of secondary line switches having access to said trunk lines, primary line switches having access to said secondary line switches, means whereby a calling subscriber can operate his primary line switch and one of said secondary line switches to connect with an idle one of said trunk lines, means for busying all the trunk lines of said group, a meter, and means rendered effective to operate said meter each time said trunk lines are made busy while the secondary line switch in use is still hunting for an idle trunk.

2. In a telephone system, subscribers' lines, a group of trunk lines, a group of rotary secondary line switches having access to said trunk lines, primary line switches having access to said group of secondary line switches, means whereby a calling subscriber can operate his primary line switch and one of said secondary line switches to connect with an idle one of said trunk lines, and means for rendering said secondary line switch inoperative in case all of said trunk lines become busy before the said secondary line switch has completed the connection.

3. In a telephone system, subscribers' lines, a group of trunk lines, a group of secondary line switches having access to said trunk lines, primary line switches having access to said secondary line switches, means whereby a calling subscriber can operate his primary line switch and one of said secondary line switches to connect with an idle one of said trunk lines, means for

rendering said secondary line switch inoperative in case all of said trunk lines become busy before the said secondary line switch has completed the connection, and means effective when said secondary line switch is made inoperative for maintaining the primary line switch in use in an operated position until said calling subscriber hangs up.

4. In a telephone system, subscribers' lines, trunk lines, groups of primary line switches and a group of rotary secondary line switches for extending calling subscribers' lines to idle trunk lines, and means responsive to a busy condition of said trunk lines for rendering inoperative one of said secondary line switches after it has been seized for extending a call.

5. In a telephone system, subscribers' lines, a group of trunk lines, a group of secondary line switches having access to said trunk lines, primary line switches having access to said secondary line switches, means whereby calling subscribers can operate their primary line switches and a plurality of said secondary line switches to connect with idle trunk lines, means for busying all the trunk lines in said group, and means for counting the number of calls that are lost due to said trunk lines being made busy before all said secondary line switches have located idle trunks.

6. In a telephone system, subscribers' lines, trunk lines, groups of primary line switches and a group of rotary secondary line switches for extending calling subscribers' lines to idle trunk lines, and means responsive to a busy condition of said trunk lines for stopping one of said secondary line switches after it has been started operating to find an idle one of said trunk lines.

7. In a telephone system, subscribers' lines, a group of trunk lines, a group of secondary line switches having access to said trunk lines, primary line switches having access to said secondary line switches, means whereby calling subscribers can operate their primary line switches and a plurality of said secondary line switches to connect with idle trunk lines, means for busying all the trunk lines in said group, and means for counting the number of calls that have been extended into connection with a secondary switch and are then lost due to said trunk lines being made busy while such secondary line switches are hunting for idle trunk lines.

In witness whereof, I hereunto subscribe my name this 27th day of February, A. D., 1922.

TALBOT G. MARTIN.
